UNITED STATES PATENT OFFICE

171,216

WARNING LIGHT OR SIMILAR ARTICLE

Algy E. Martin, North Hollywood, and Mearl D. Lorimor, Van Nuys, Calif., assignors to Light Products, Inc., Beverly Hills, Calif., a corporation of California

Application June 1, 1953, Serial No. 25,274

Term of patent 14 years

(Cl. D72—1)

To all whom it may concern:

Be it known that we, Algy E. Martin and Mearl D. Lorimor, citizens of the United States, residing in North Hollywood and Van Nuys, respectively, county of Los Angeles, State of California, have invented a new, original, and ornamental Design for Warning Light or Similar Article, of which the following is a specification, reference being had to the accompanying drawing forming part thereof.

Fig. 1 is a side elevational view of a warning light showing my new design;

Fig. 2 is a front end elevational view;

Fig. 3 is a rear end elevational view; and

We claim:

The ornamental design for a warning light or similar article, substantially as shown.

ALGY E. MARTIN.
MEARL D. LORIMOR.
